PAPER-LINING MACHINE.

1,407,317.

Specification of Letters Patent. Patented Feb. 21, 1922.

Application filed July 3, 1917. Serial No. 178,370.

To all whom it may concern:

Be it known that we, GEORGE W. BLANKENHORN and THOMAS CASTBERG, citizens of the United States, residing at the city and county of San Francisco and State of California, have invented new and useful Improvements in Paper-Lining Machines, of which the following is a specification.

This invention relates to a paper lining machine.

One of the objects of the present invention is to provide a simple, compact machine of the rotary type for cutting paper gaskets and inserting the same in can ends, and particularly to provide an improved form of cutting mechanism. Another object of the invention is to provide an improved mechanism for delivering a can end to each die in successive order, and in conjunction therewith to provide means for forcing each can end up against its die and simultaneously centering the end with relation to the die. Another object of the invention is to provide an improved mechanism for ensuring a perfect transfer of the gasket from the die to the can end. Further objects will hereinafter appear.

The invention consists of the parts and the construction and combination of parts as hereinafter more fully described and claimed, having reference to the accompanying drawings, in which—

Fig. 1 is a central, vertical, longitudinal section through the machine.

Fig. 2 is an enlarged detail view of the can end chute, the feeding mechanism for delivering the can ends one by one to the chute, and also a section of the die showing the same in the position where the can end is engaged and removed from the upper half of the chute.

Fig. 3 is a plan view of the can end feeding mechanism.

Fig. 4 is a plan view of the machine partly in section.

Fig. 5 is an enlarged detail view, showing the relative position between a die and the platen during the cutting operation.

Fig. 6 is a plan section of the can end feeding chute, taken on line 6—6 of Fig. 2.

Referring to the drawings in detail, A indicates a pair of vertically disposed inter-spaced frames in which is journaled a driv-

ing shaft 2. Keyed or otherwise secured upon said shaft, between the frames, is a wheel 3 hereinafter to be known as the die wheel, and suitably secured on said wheel is a plurality of die members generally indicated at B. Pivotedly mounted, as at 4, in the upper part of the frame is an arm 5 and journaled between downwardly extending lugs 6, formed on the arm, is a roller or platen 7 which is adapted to cooperate with each individual die to cut a paper gasket, hereinafter to be described, from a continuous web of paper 8 taken from a roller 9 or other convenient source of supply.

Formed integral with the die wheel, on each side thereof or otherwise secured, is a continuous track member 10, and mounted interiorly of each track member, in alignment with each die, is an adjustable track member 11. There are two adjustable track members 11 one on each side of each die and each track member is adapted to be raised or lowered with relation to the cutting edges of the die by means of a pair of set-screws 12, and secured to the track members 10 when adjusted by means of a pair of clamping screws 13. Each die is provided with a pair of annular cutting edges 14 and 15 which are spaced apart to form an annular recess 16. Mounted in said recess is a knock-out ring 17, and connected with said knock-out ring are four pins 18 secured to a knock-out plate 19 which carries a cam 20. The annular cutting edges 14 and 16 represent a straight cutting face as they are both disposed on a horizontal plane when the die assumes the position shown in Fig. 5. The upper faces of the adjustable tracks are, therefore, also straight and will assume a plane parallel with the cutting edges of the die. The adjustable track members are provided for the purpose of supporting the platen 7 during the cutting operation, that is, when a die is passing under the platen.

In actual practice it has been found that the upper surfaces of the adjustable tracks may assume a plane from 1/1000 to 3/1000 of an inch above the surface of the cutting edges of the die, thereby holding the platen out of contact with the cutting edges and preventing injury to same or cutting up of the face of the platen. The average paper employed for cutting ring liners for can

ends measures approximately 10/1000 of an inch. The paper during its passage between the platen and the die is partially severed and is simultaneously forced into the annular recess of the die, where it is clamped to such an extent as to rip the ring liner from the web during the separation of the web and the dies. The ring liner thus cut and ripped from the continuous web is retained 10 until the die reaches the dotted line position shown at B' in Fig. 2 where it is knocked out or transferred to the can end.

A can end is first delivered to the die and centered with relation to same before the 15 transfer of the liner takes place and this is accomplished in the following manner: Positioned on one side of the die wheel is a can end chute, consisting of an upper part 21 and a lower section 22. Mounted above 20 the upper end of the chute is a can end feeding and separating device, generally indicated at C, which is adapted to receive a can end stack. This can end separating and feeding mechanism is shown in our patent 25 No. 1,272,764, issued July 16, 1918 entitled "Can end separator and feeder," which consists briefly of a pair of continuously revolving shafts 24 each supporting a pair of superposed supporting and feeding disks 25 30 and 26. These disks revolve in unison and are adapted to alternately separate and release the can ends contained in the stack one by one.

Each can end, when released, drops into 35 the upper end 21 of the can end chute and is here temporarily stopped by a pair of revolving disks 27 and 28. These disks are secured upon the feeding shafts 24 and as the disks are reduced in diameter or approximately half of each disk is cut away, as at 40 29, it can readily be seen that the enlarged portion of each disk will form a stop for the can end in the chute, while the reduced portion will permit the can ends to drop 45 through to a point where they are received by a second temporary support consisting of a pair of yielding fingers 30. These fingers project through slots 31 formed in the can end chute and each finger is pivotally 50 mounted in a bracket 32 formed on the rear side of the chute; the fingers being normally retained in the slots by means of springs 33 (see Fig. 6). A can end when released from the feeding disks 25 and 26 will first be received 55 by the upper temporary supporting members 27 and 28 but are here released and permitted to drop to the lower supporting members 30 each time the feeding shafts make one revolution.

60 The object of providing an intermediate stop positioned between the feeding disks and the yielding fingers 30 is to avoid too great a drop; that is, it has been found that a can end dropped directly from the feeding 65 disks to the fingers 30 gains sufficient mo-

mentum to rebound in some instances, while in other instances the ends have a tendency to spread the fingers and partly clamp the end. In other words, a high drop does not permit of a uniform feeding or positioning 70 of the can ends with relation to the fingers 30. The provision of the intermediate stop reduces the distance or drop to one half and entirely eliminates the tendency of any rebound or spreading of the fingers. Each 75 can end received by the fingers will, therefore, assume a fixed position which is of great importance when delivery is made to each die member.

The can ends employed in the present instance are provided with an annular recess, such as shown at 36. This recess, in actual practice, is not only provided for the purpose of strengthening and reinforcing the end but also for the purpose of producing 80 an ornamental effect. This recess has been taken advantage of to permit the removal of each end with relation to the fingers 30 and also to permit each end to be centered 85 with relation to the die which receives it. 90

The removal of each can end from the position shown at 34 in Fig. 2 and the centering of the ends with relation to the dies is accomplished in the following manner: Slidably mounted centrally of the die is a stem 37, and secured on the outer end of this stem is an enlarged hub member 38 and a pad 39. A spring 40, interposed between the hub and the recess formed in the die, serves to normally force it outwardly into the position 100 shown in Fig. 2 while the stop 41 limits said outward movement. The outer face of the pad conforms with the contour of the end and is provided with an annular bead 42 which is adapted to engage the annular recess 36 formed in each end. 105

A die during its movement will finally assume the full line position shown in Fig. 2 where the annular bead 42 on the pad will engage the annular recess 36 formed in the 110 end. A positive engagement is thereby made which permits the pad to pull the end away from the yielding fingers 30. These fingers merely spread or swing about their pivots 32 when an end is removed by a pad 115 and as they are both spring actuated, it can readily be seen that they will immediately snap back into position to receive the next end the moment the end previously received is removed, a positive timing between the 120 feeding shafts 24 and the main shaft 2 being maintained by the sprocket gear drive shown at 45. That is, the timing between the arrival of a die at the point shown by full lines in Fig. 2 is such that an end received by the temporary supporting members 27 and 28 will not be released until the lower end 34 has been removed and the fingers 30 return to receiving position. 125

The end, after it has been engaged by 130

the pad and pulled away from the fingers 30, passes down through the lower portion of the can end chute shown at 23. This portion of the chute depresses gradually inwardly towards the die wheel and, therefore, bears with sufficient pressure upon the can end to force the pad into a seat or recess 46 formed in the die for its reception. The can end is at the same time 10 centered with relation to the die as the annular bead 42 on the pad enters the annular groove 36 formed in the end, the centering action being further increased by an annular shoulder 47 formed on the end 15 entering an annular recess 48 which is formed inside of and concentric with the inner cutting edge 14 of the die. A can end is forced into position by the time the die reaches the dotted line position 20 shown at B' and is, therefore, ready to receive the paper gasket cut during the passage of the die under the platen 7. This transfer is accomplished by the cam 20 striking a roller 20^a. This engagement of 25 the cam and roller forces the knock-out plate 19, together with the pins 18 and the knock-out ring 17, outwardly, thereby forcing the paper gasket out of the annular recess 16 and into the annular recess 30 34^a formed in the outer edge of the can end.

One, two or more rollers 20^a may be provided, as shown in Fig. 1. That is, the knock-out ring may be depressed or forced 35 outwardly from the recess 16 a plurality of times. This has been found advantageous in actual practice as it insures a positive transfer of the paper gasket from the annular recess 16 to the annular recess 34^a 40 of the end. This will better be understood from the following description: The outer edge of the can is flanged inwardly, as shown at 34^b, for the purpose of preventing the gasket from being accidentally removed 45 from the outer recess of the can end once the paper gasket has been inserted. The outer diameter of the paper gasket when cut should, therefore, be of larger diameter than the inner diameter of the turned annular 50 flange 34^b to permit the paper gasket when inserted to be snapped under said flange.

This annular flange, as previously stated, retains the gasket from accidental movement after being once inserted but it is a 55 source of considerable trouble during the transferring operation of the gasket from the die to the can end; that is, the gasket during the transferring operation has a tendency to disarrange itself to such an extent that a portion of same will sometimes 60 overlie the annular flange 34^b of the can end, thus leaving the gasket in a position where it can be easily removed. This disadvantage 65 has been overcome by providing a double knock-out or the two rollers 20^a shown. Two

or more reciprocations transmitted to the knock-out ring 17 seems to overcome this difficulty inasmuch as it forces such portions of the gasket under the annular flange 34^b which might otherwise have a tendency 70 to remain outside.

The can end, after receiving the gasket, is finally released from the lower end of the chute 23 and may here be deposited in a box or delivered to a conveyer belt which 75 will carry the ends away from the machine. The pad 39 will, of course, spring out the moment it moves out of alignment with the chute 23 and is, therefore, in readiness to receive a second end when it turns into position with relation to the can end chute, as shown in Fig. 2. The spring 40 automatically projects the pad each time pressure is removed, while springs 40^a, surrounding the pins 18, automatically retract 80 the knock-out ring 17 each time it has been projected by a roller 20^a. The rollers 20^a are journaled in an arm 20^b, which in turn is suitably secured upon a stationary sleeve 90 secured against revolution in one of the bearings of the main frame A, as shown in Figs. 1 and 4.

The cutting operation, as previously stated, takes place while the die passes under the platen 7. Considerable pressure is 95 necessarily exerted upon the platen or roller 7 while a die is passing thereunder to permit the platen to sever and force the paper into the annular recess 16 of the die. This pressure is applied by means of a spring 60 100 interposed between the outer end of the arm 5 and a top plate 61 connecting the upper ends of the frames A; a set-screw 62 being provided for the purpose of adjusting the tension of the spring. A single 105 spring is provided and as this is centrally positioned with relation to the arm 5 and the platen 7 carried thereby a uniform tension or pressure is exerted between the platen and the cutting edges of each die. 110 The spring will at the same time permit the arm 5 to swing or oscillate about the pivotal connection 4 when the die passes, and as it has been found that more pressure is required at each end of the die, it can readily 115 be seen that this condition is ideal, that is, each die presents a straight or plain cutting surface, and as each die swings in a true circle each end of each die swings in a circle having a larger radius than the center portion. A die on entering under the platen 7 will, therefore, first present its highest point and consequently raise the platen, together with the arm 5, against the tension of the spring 7, thereby exerting a greater pressure on the rounded end 120 of the die.

A continued movement of a die, for instance to the position shown in Fig. 1, brings the smallest radius of the die into alignment 130

with the platen and permits it to recede and decrease the tension of the spring 60. A further movement of a die, when passing away or leaving the platen, again brings the 5 high point of the die into register and will consequently again raise the platen and compress the spring. The spring pressure is, therefore, greatest at each end of the die and smallest when passing over the 10 center portion of same. This condition is ideal as it exerts the greatest pressure where it is needed and the least pressure where less pressure is required.

The pivotal mounting of the arm supporting the platen eliminates the necessity of providing dies having a contour or cutting face equal to the radius upon which it swings, thereby lessening the cost of construction and maintenance and, furthermore, making 15 it possible to deliver can ends which may be forced or held directly against the face of each die while transfer of a gasket is taking place. The cutting of a gasket and the transferring of same directly from the 20 die into a can end is in this instance made possible; first, by forming dies having straight, parallel cutting edges; and, second by providing means for delivering ends, centering same and forcing them directly 25 against the face of the dies, thereby accomplishing the whole operation in less than half a revolution of the die wheel or what may be termed a single operation, something heretofore never accomplished nor thought 30 possible while the dies are continuously moving.

All means heretofore employed, with the exception of the co-pending application referred to, must stop while the operation of 40 cutting the gasket takes place and must also stop while transferring of the gasket is taking place. The present machine is designed to continuously rotate, said rotation being transmitted through a pulley 70 which is 45 cured upon the main driving shaft 2 or any other suitable means. The capacity of the machine is, therefore, greatly increased when compared with machines having an intermittent movement as the time required for stopping is entirely eliminated. The mechanism 50 for delivering the can ends to the dies is positively driven from the driving shaft 2 and therefore leaves all operations performed automatic and positive.

55 The waste paper, comprising the web 8 from which the gaskets are cut, together with the center blank, may be removed in any suitable manner and any suitable means may be provided for feeding the web between the dies and the platen. While the platen is here shown as positioned in the upper portion of the frame, we wish it understood that it may be positioned on either side or on the bottom, the bottom being preferable if any as the waste paper can at this

point be more readily discharged. The position of the can end chute 23 and the feeding mechanism employed in connection therewith may also be placed at any point around the periphery of the die wheel and 70 a spring 65 is preferably interposed between the chute and the frame supporting the same to permit the chute to yield if two ends should accidentally enter the chute.

We also wish it understood that the materials and finish of the several parts of the machine may be such as the experience and judgment of the manufacturer may dictate.

Having thus described our invention, what we claim and desire to secure by Letters Patent is:

1. In a paper lining machine, a die adapted to cut and receive a gasket, means for delivering a can end to the die, and yieldable means on the die for centering the end 85 with relation to the gasket.

2. In a paper lining machine, a continuously moving die adapted to cut and receive a gasket, means for delivering a can end to the die, and means on the die for 90 centering the end with relation to the gasket.

3. In a paper lining machine, a cutting die, a resilient member carried by the die, and means on said member for centering a can end with relation to the die. 95

4. In a paper lining machine, a cutting die, a reciprocally mounted pad member centrally positioned in the die; a spring interposed between the die and pad member, and means on the pad for centering a can end 100 with relation to the pad and the die.

5. In a paper lining machine, a die wheel, a plurality of cutting dies on said wheel, a chute mounted on one side of the wheel, means for delivering can ends to said chute 105 one by one, a member in the chute adapted to receive and temporarily support the ends one by one, and means on each die for removing the ends one by one.

6. In a paper lining machine a die wheel, 110 a plurality of cutting dies on said wheel, a chute mounted on one side of the wheel, means for delivering can ends to said chute one by one, a member in the chute adapted to receive and temporarily support the ends 115 one by one, and a yieldably mounted member on each die adapted to remove the ends one by one from the temporary supporting member.

7. In a paper lining machine, a die wheel, 120 a plurality of cutting dies on said wheel, a chute mounted on one side of the wheel, means for delivering can ends to said chute one by one, a member in the chute adapted to receive and temporarily support the ends 125 one by one, and a yieldably mounted pad member in each die adapted to remove the can ends from the temporary support one by one, and also adapted to center each end with relation to its die. 130

8. In a paper lining machine, a movable cutting die, a chute mounted in the path of travel of said die, a member in the chute adapted to receive and temporarily support can ends one by one, and means on the die for removing the ends from the supporting member one by one.
9. In a paper lining machine, a continuously moving cutting die, a chute mounted in the path of travel of said die, a member in the chute adapted to receive and temporarily support can ends one by one, and means for removing the ends from the supporting member one by one, said means adapted to center each end with relation to the die.
10. In a paper lining machine, a continuously moving cutting die adapted to cut and receive a paper gasket, a chute mounted in the path of travel of said die, a yielding member in the chute adapted to receive and temporarily support can ends one by one, and means operable in conjunction with the die for removing the ends from the yielding supporting member one by one.
11. In a paper lining machine, a continuously moving die adapted to cut and receive a paper gasket, a chute mounted in the path of travel of said die, a yielding member in the chute adapted to receive and temporarily support can ends one by one, and means operable in conjunction with the die for removing the ends from the yielding supporting member one by one, said yielding supporting member comprising a pair of pivotally mounted fingers between which a can end is supported, and a spring connected with each finger adapted to normally hold the fingers in a position where they will support the can ends received.
12. In a cutting machine, a frame, a die wheel journaled to rotate in the frame, a plurality of straight faced cutting dies mounted on the wheel, a platen adjacent the wheel, over which the dies are adapted to pass during the rotation of the wheel, supporting members adjacent each die with which the platen is adapted to engage, said supporting members adapted to prevent engagement of the platen with the dies, and means for maintaining the platen in engagement with said members during the rotation of the wheel.
13. In a cutting machine, a frame, a die wheel journaled to rotate in the frame, a plurality of straight faced cutting dies mounted on the wheel, a platen adjacent the wheel, over which the dies are adapted to pass during the rotation of the wheel, supporting members adjacent each die with which the platen is adapted to engage, said supporting members adapted to prevent engagement of the platen with the dies, means for maintaining the platen in engagement with said members during the rotation of the wheel, and means for adjusting said sup-
- porting members to form a fixed spacing between the cutting edges on the dies and the face of the platen.
14. In a paper lining machine, a frame, an arm pivotally mounted at one end of the frame and having the opposite end arranged so that it is free to oscillate in an arc, a cylindrical platen member journaled to rotate in the free end of the arm, a movable flat-faced cutting die adapted to pass over the platen member a pair of shoes positioned one on each side of the die, adapted to prevent contact of the platen and the cutting edge of the die and means for adjusting the position of each shoe to maintain a fixed spacing between the face of the platen and the cutting edge of the die.
15. In a paper lining machine, a continuous revolving rotor, a plurality of dies carried by said rotor, a can end chute adjacent one side of the rotor, means for delivering can ends to said chute, one by one, a rotating support on said chute adapted to temporarily interrupt the passage of the can ends through the chute, a yieldable supporting member adapted to receive the can ends one by one when released by the temporary supporting member, and means on each die for engaging the can ends and removing the same from the yieldable support.
16. In a paper lining machine, a movable die carrier, a plurality of dies on said carrier adapted to cut and receive paper gaskets, a can end chute, means for delivering can ends thereto one by one, a temporary support and retainer in the chute adapted to receive the can ends one by one, and a member on each die adapted to engage and remove the can ends from the temporary retainer one by one.
17. In a paper lining machine, a movable die carrier, a plurality of dies on said carrier adapted to cut and receive paper gaskets, a can end chute, means for delivering can ends thereto one by one, a temporary support and retainer in the chute adapted to receive the can ends one by one, and a yieldable pad member on each die adapted to engage and remove the can ends from the temporary retainer one by one.
18. In a paper lining machine, a movable die carrier, a plurality of dies on said carrier adapted to cut and receive paper gaskets, a can end chute, means for delivering can ends thereto one by one, a temporary support and retainer in the chute adapted to receive the can ends one by one, a yieldable pad member on each die adapted to engage and remove the can ends from the temporary retainer one by one, and adapted to hold the ends when removed and center the same with relation to the dies.
19. In a cutting machine, a frame, a die wheel journaled to rotate in the frame, a plurality of straight-faced cutting dies

mounted on the wheel, an arm pivotally mounted in the frame, a roller platen journaled in said arm, supporting members adjacent to each die with which the roller is adapted to engage, means for holding the roller in engagement with said supporting members, and means for adjusting said members to form a spacing between the cutting edges on the die and the face of the roller.

20. In a cutting machine a frame, a die wheel journaled to rotate in the frame, a plurality of straight-faced cutting dies mounted on the wheel, an arm pivotally mounted in the frame, a roller platen journaled in said arm, supporting members adjacent to each die with which the roller is adapted to engage, means for holding the roller in engagement with said supporting members, and means for adjusting said members to maintain a fixed relation between the cutting edges of the dies and the face of the roller.

21. In a cutting machine, a frame, a die wheel journaled to rotate in the frame, a plurality of straight-faced cutting dies mounted on the wheel, a roller under which each die passes during the rotation of the wheel, a pivotally mounted arm supporting said roller, a spring engageable with said arm, means for adjusting the tension of said spring, and a supporting member adjacent to each die adapted to maintain a fixed relation between the cutting edges of the die and the surface of the roller.

22. In a paper lining machine, a frame an arm pivotally mounted at one end in the frame and having the opposite end arranged so that it is free to oscillate, a platen member journaled to rotate in the free end of the arm, a movable flat faced cutting die adapted to pass under the platen, a spring arranged to exert its pressure on the free end of the arm and to form a resilient support for the platen member, and means for preventing physical contact between the platen and the die.

23. In a paper lining machine, a frame, an arm pivotally mounted at one end in the frame and having the opposite end arranged so that it is free to oscillate, a platen member journaled to rotate in the free end of the arm, a movable flat faced cutting die adapted to pass under the platen member, a spring arranged to exert its pressure on the free end of the arm at a point centrally of the platen member and to form a resilient support for the platen member, and means for preventing physical contact between the platen and the die.

24. In a paper lining machine, a frame, an arm pivotally mounted at one end in the frame and having the opposite end arranged so that it is free to oscillate, a platen member journaled to rotate in the free end of the

arm, a movable flat-faced cutting die adapted to pass under the platen member, a single spring arranged to exert its pressure on the free end of the arm at a point centrally of the platen member and to form a resilient support for the platen member and means for adjusting the tension of said spring and means for preventing physical contact between the platen and the die.

25. In a paper lining machine, a frame, an arm pivotally mounted at one end in the frame and having the opposite end arranged so that it is free to oscillate, a platen member journaled to rotate in the free end of the arm, a movable flat-faced cutting die adapted to pass under the platen member, a spring arranged to exert its pressure on the free end of the arm, and means for preventing the platen from contacting with the die.

26. In a paper lining machine a yieldably mounted platen member, a cutting member, means adjacent the cutting member for maintaining the platen member out of contact with the cutting member, means for moving one member with relation to the other, and means for feeding the material to be cut between said members.

27. In a paper lining machine a yieldably mounted platen member, a cutting member, means adjacent the cutting member for maintaining a predetermined spacing between the surface of the platen and the cutting edge of the cutting member, means for moving the cutting member with relation to the platen, and means for feeding the material to be cut between said members.

28. In a paper lining machine, a platen member, a cutting member, means adjacent the cutting member for maintaining a predetermined spacing between the surface of the platen and the cutting edge of the cutting member, and means for moving one member with relation to the other and simultaneously permitting the feeding of material to be cut between the members.

29. The combination with a die having a flat-faced cutting edge, of a roller movable and yieldable with relation to the die, and a supporting member adjacent to the die adapted to hold the roller out of engagement or contact with the cutting edge.

30. The combination with a die having a flat-faced cutting edge, of a roller movable and yieldable with relation to the die, a member adjacent to the die adapted to support the roller, and means for adjusting the position of said member to adjust the relation between the die and the roller.

31. In a paper lining machine, a continuously moving die adapted to cut and receive a paper gasket, means for delivering a can end to the die, means on the die for centering the end with relation to the gasket

in the die, means for forcing the can end against the die, a knock-out ring in the die adapted to eject the gasket from the die and insert it directly into an annular channel formed in the can end, and means for reciprocating the knock-out ring to cause said ejection and insertion.

32. In a paper lining machine, a die adapted to cut and receive a paper gasket, means for delivering a can end to the die, means for centering the end with relation to the gasket in the die, stationary means for forcing the can end against the die, a knock-out ring in the die adapted to eject the gasket from the die and insert it directly into an annular channel formed in the can end, and means for reciprocating the knock-out ring a plurality of times to cause said ejection and to insure a perfect insertion.

33. In a paper lining machine, a die carrier, a plurality of dies on said carrier, a can end chute mounted in the path of travel of the dies, means for delivering can ends one by one to the chute, a pair of revolving discs in the chute adapted to temporarily support and then release the can ends one by one, and a pair of yielding fingers at the lower end of the chute adapted to receive the can ends one by one and to support the same until removed by the die members.

34. In a paper lining machine, a die carrier, a cylindrical platen mounted adjacent to the die carrier, a plurality of die members on the carrier adapted to pass in successive order under the platen, a pair of continuous cutting edges and an intermediate channel formed in each die, means for feeding a paper sheet between the platen and the dies, means for exerting pressure on the platen to permit the cutting edges of the die to cut a paper gasket and simultaneously to permit the platen to force said gasket into the channel of the die, a can end chute mounted in the path of travel of the dies, means for delivering can ends to said chute one by one, a supporting member in the chute adapted to receive and momentarily support the can ends one by one, and means operable in conjunction with each die for removing the can ends one by one from said supporting member.

35. In a paper lining machine, a die carrier, a cylindrical platen mounted adjacent to the die carrier, a plurality of die members on the carrier adapted to pass in successive order under the platen, a pair of continuous cutting edges and an intermediate channel formed in each die, means for feeding a paper sheet between the platen and the dies, means for exerting pressure on the platen to permit the cutting edges of the die to cut a paper gasket and simultaneously to permit the platen to force said gasket into the channel of the die, a can end chute mounted in the path of travel of the dies,

means for delivering can ends to said chute one by one, a supporting member in the chute adapted to receive and momentarily support the can ends one by one, and means on each die for removing the ends from said supporting member one by one and also adapted to secure and center the ends with relation to the dies.

36. In a paper lining machine, a die carrier, a cylindrical platen mounted adjacent to the die carrier, a plurality of die members on the carrier adapted to pass in successive order under the platen, a pair of continuous cutting edges and an intermediate channel formed in each die, means for feeding a paper sheet between the platen and the dies, means for exerting pressure on the platen to permit the cutting edges of the die to cut a paper gasket and simultaneously to permit the platen to force said gasket into the channel of the die, a can end chute mounted in the path of travel of the dies, means for delivering can ends to said chute one by one, a supporting member in the chute adapted to receive and momentarily support the can ends one by one, means on each die for removing the ends from said supporting member one by one and also adapted to secure and center the ends with relation to the dies, and means for ejecting the paper gaskets and forcing the same into the can ends during said period of engagement.

37. In a paper lining machine, a die carrier, a cylindrical platen mounted adjacent to the die carrier, a plurality of die members on the carrier adapted to pass in successive order under the platen, a pair of continuous cutting edges and an intermediate channel formed in each die, means for feeding a paper sheet between the platen and the dies, means for exerting pressure on the platen to permit the cutting edges of the die to cut a paper gasket and simultaneously to permit the platen to force said gasket into the channel of the die, a can end chute mounted in the path of travel of the dies, means for delivering can ends to said chute one by one, a supporting member in the chute adapted to receive and momentarily support the can ends one by one, means on each die for removing the ends from said supporting member one by one and also adapted to secure and center the ends with relation to the dies, an ejecting member in each side for transferring the gasket from the die to the can end during said period of engagement, and means for operating the ejecting member in each die a plurality of times during said period of engagement to insure a perfect transfer of the gasket.

38. In a paper lining machine, a die carrier, a cylindrical platen mounted adjacent to the die carrier, a plurality of die members on the carrier adapted to pass in successive order under the platen, a pair of continuous

cutting edges and an intermediate channel formed in each die, means for feeding a paper sheet between the platen and the dies, means for exerting pressure on the platen to 5 permit the cutting edges of the die to cut a paper gasket and simultaneously to permit the platen to force said gasket into the channel of the die, a can end chute mounted in the path of travel of the dies, means for delivering can ends to said chute one by one, a supporting member in the chute adapted to receive and momentarily support the can ends one by one, a resilient pad member in 10 each die, means on each pad for engaging a can end and removing the same from the temporary supporting member in the chute, said means also adapted to center and momentarily secure the can with relation to the die, a knock-out ring in each die, and a cam 15 member adapted to reciprocate the knock-out ring to transfer the gasket from the die to the can end.

39. In a paper lining machine, a die carrier, a cylindrical platen mounted adjacent to the die carrier, a plurality of die members on the carrier adapted to pass in successive order under the platen, a pair of continuous cutting edges and an intermediate channel formed in each die, means for feeding a 20 paper sheet between the platen and the dies, means for exerting pressure on the platen to permit the cutting edges of the die to cut a paper gasket and simultaneously to permit the platen to force said gasket into the channel of the die, a can end chute mounted in the path of travel of the dies, means for delivering can ends to said chute one by one, a supporting member in the chute adapted to receive and momentarily support the can 25 ends one by one, a resilient pad member in each die, means on each pad for engaging a can end and removing the same from the temporary supporting member in the chute, said means also adapted to center and momentarily secure the can with relation to the die, a knock-out ring in each die, a stationary member having a plurality of cans formed thereon adapted to force the knock-out ring in an outward direction a plurality of times 30 to eject the gasket from the die and transfer it to the can end, and means for automatically releasing the can ends and discharging same from the chute after the gaskets have been inserted.

40. In a paper lining machine, a die carrier, a cylindrical platen mounted adjacent to the die carrier, a plurality of die members 35 on the carrier adapted to pass in successive order under the platen, a pair of continuous cutting edges and an intermediate channel formed in each die, means for feeding a paper sheet between the platen and the dies, means for exerting pressure on the platen to 40 permit the cutting edges of the die to cut a paper gasket and simultaneously to permit the platen to force said gasket into the channel of the die, a can end chute mounted in 45 the path of travel of the dies, means for delivering can ends to said chute one by one, a supporting member in the chute adapted to receive and momentarily support the can ends one by one, a resilient pad member in each die, means on each pad for engaging a can end and removing the same from the temporary supporting member in the chute, said means also adapted to center and momentarily secure the can with relation to the die, a knock-out ring in each die, a stationary member having a plurality of cans formed thereon adapted to force the knock-out ring in an outward direction a plurality of times 50 to eject the gasket from the die and transfer it to the can end, and means for automatically releasing the can ends and discharging same from the chute after the gaskets have been inserted.

41. In a paper lining machine, a die carrier, a cylindrical platen mounted adjacent to the die carrier, a plurality of die members on the carrier adapted to pass in successive order under the platen, a pair of continuous cutting edges and an intermediate channel formed in each die, means for feeding a 55 paper sheet between the platen and the dies, means for exerting pressure on the platen to permit the cutting edges of the die to cut a paper gasket and simultaneously to permit the platen to force said gasket into the channel of the die, a can end chute mounted in the path of travel of the dies, means for delivering can ends to said chute one by one, a supporting member in the chute adapted to receive and momentarily support the can 60 ends one by one, a resilient pad member in each die, means on each pad for engaging a can end and removing the same from the temporary supporting member in the chute, said means also adapted to center and momentarily secure the can with relation to the die, a knock-out ring in each die, and means for automatically releasing the can ends and discharging same from the chute after the gaskets have been inserted.

42. A mechanism for cutting ring liners including a traveling die member, a rotary platen arranged in juxtaposition to the path of travel to the die member, a support for the die member, an adjustable means on 65 said support for supporting the platen when the die passes over the same, said support adapted to be so adjusted relative to the die as to hold the platen out of contact with the die and yet sufficiently close to 70 the die to sever paper passed between the die and platen without actual physical contact of the die member and the platen.

43. In a can end liner cutting mechanism, the combination of a continuously traveling flat-faced die member, a roller platen, means for feeding paper between the die and platen, means by which the die member 75

- is maintained in cutting relation to the platen member so as to sever the paper when the die member traverses the platen and yet the die member and platen remain out of actual physical contact. 5
44. In a can end lining machine, the combination of a rotary carrier having continuous motion, a die member carried thereby, a platen with which the die member is adapted to cooperate to cut the liners, and means carried by the rotary carrier for maintaining the platen out of actual contact with but in cutting relation to the die member. 10
45. In a can end lining machine, the combination of a rotary carrier having continuous motion, a die member carried thereby, a platen with which the die member is adapted to cooperate to cut the liners, means carried by the rotary carrier for maintaining the platen out of actual contact with but in cutting relation to the die member, a can end carrying means delivering the cans in juxtaposition to the die with means carried by 20 the die for delivering the liners into the can ends. 25
46. In a can end lining machine, the combination of a rotary carrier, a flat-faced die member carried thereby, a platen disposed in tangential relation to the path of travel of the die member, said platen mounted for arcuate movement towards and from the die member, means for preventing the platen from contacting with the die and a resilient member adapted to maintain the platen in contact with said last named means. 30
47. In a machine for applying ring liners to can ends, the combination of a traveling die member, associated mechanism for cutting and receiving a liner into the die member, means for delivering can ends singly to the die member, a pad in each die for engaging the ends and whereby a can end is centered with respect to the die and the can end is caused to progress with the die, and 35
- means for transferring the liner from the die to the can end. 48. In a paper lining machine a die adapted to cut and receive a gasket, means for delivering a can end to the die, a yieldable pad 50 member in the die and an annular ridge on said die for engaging and centering can ends. 49. In a paper lining machine a movable die adapted to cut and receive a paper 55 gasket, a platen under which the die passes during the cutting operation, means for maintaining the platen out of physical contact with the die, means for delivering a can end into alignment with the die after a gasket has been cut, and means for forcing 60 the end snugly against the die. 50. In a paper lining machine a movable die adapted to cut and receive a paper 65 gasket, a platen under which the die passes during the cutting operation, means for maintaining the platen out of physical contact with the die, means for delivering a can end into alignment with the die after a gasket has been cut, means for forcing the 70 end snugly against the die, and means for transferring the gasket to the end. 51. In a paper lining machine a movable die adapted to cut and receive a paper 75 gasket, a platen under which the die passes during the cutting operation, means for maintaining the platen out of physical contact with the die, means for delivering a can end into alignment with the die after a gasket has been cut, and means for transferring the gasket to the end. 80
- In testimony whereof we have hereunto set our hands in the presence of two subscribing witnesses.
